JOHN W. SOHN, OF ROXBOROUGH, PENNSYLVANIA, ASSIGNOR TO A. T. BAKER & COMPANY, OF MANAYUNK, PHILADELPHIA, PENNSYLVANIA, A COPARTNERSHIP COMPOSED OF ALFRED T. BAKER AND ALFRED T. BAKER, JR.

PILE FABRIC.

1,270,229.

Specification of Letters Patent. Patented June 18, 1918.

Application filed March 28, 1917. Serial No. 157,891.

To all whom it may concern:

Be it known that I, JOHN W. SOHN, a citizen of the United States, residing at Roxborough, county of Philadelphia, and State of Pennsylvania, have invented a new and useful Improvement in Pile Fabrics, of which the following is a full, clear, and exact description, reference being had to the accompanying drawings, which form a part 10 of this specification.

My invention relates to cut pile fabrics wherein two backing fabrics, connected by pile warps extending continuously through both fabrics and from one to the other, are 15 cut in a plane midway between and parallel to both backing fabrics to form two halves, each constituting a complete finished fabric having on one face a multitude of short upright cut pile ends.

20 The object of the invention is to so weave the fabric that with the employment of eight series of pile warp threads, of which one of each series is arranged in a set of eight pile warp threads, a relatively full 25 tufted face will be produced with a minimum weight of warp in the backings. A further object of the invention is to so produce a smooth tufted face without objectionable ridges.

30 The fabric displays characteristics common to woven pile fabrics in that it is composed of a top backing, a bottom backing, pile warp threads which interlace with the weft or filler threads of both backings and 35 also extend between the top and bottom fabrics, and binder warp threads each of which extend through only a single backing. The fabric is conveniently woven on a double loom, two filler shorts or weft picks 40 being thrown simultaneously.

A preferred embodiment of the invention is shown in the accompanying drawings, in which:—

Figure 1 is a cross-section through the 45 fabric parallel to the warp showing four pile warp threads of a set and the corresponding binder or ground warp.

Fig. 2 is a section parallel to and between the top and bottom fabrics, looking in the 50 direction of the arrow, Fig. 1.

I employ, as hereinbefore stated, eight pile warp threads in a set, marked respectively 1, 2, 3, 4, 5, 6, 7 and 8. In Fig. 1, for purposes of clearness, only four pile

threads are shown, it being understood, 55 however, that where any pile thread of the four shown engages a weft of one backing in a particular way, a corresponding pile thread, not shown, engages a weft of the other backing in the same way. Thus, in 60 Fig. 2, the interlacing of pile warps 5, 6, 7 and 8 with the weft of the backing shown is precisely the same as the interlacing of pile warps 1, 2, 3 and 4 with the corresponding pile warps of the backing not shown. 65

The weft threads of the upper backing are marked *a*, *b*, *c*, *d*, *e*, *f*, *g*, *h*, and of the lower backing *i*, *j*, *k*, *l*, *m*, *n*, *o*, *p*.

Each pile thread extends successively over, under and over three successive weft 70 threads of one backing fabric, thence to the other backing and successively over, under and over three successive weft threads thereof and thence across to the first backing. Pile thread 2 intersects the weft in the same 75 manner as, but two picks in advance of, pile thread 1. Pile thread 3 follows the same course but two picks in advance of the pile thread 2. Pile thread 4 follows the same course but one pick in advance of one of the 80 other pile threads, say the first, as shown. Pile thread 4 also operates as a pair with one of the other pile threads, say the third, as shown: that is, along any given number of pairs of weft threads, pile thread 4 intersects the weft of one backing in the same manner that pile warp 3 intersects the weft of the other backing. This causes pile 85 thread 4 to intersect pile thread 3 between the two backings and also to bind in, along 90 successive weft threads, pile threads 1 and 2, either or both, thus performing, in a measure, a function analogous to that of a ground, binder or backing warp for exactly half of the other three pile threads, be- 95 sides being always bound in itself by one of the other pile threads.

As hereinbefore stated pile threads 5, 6, 7 and 8 operate in pairs with pile threads 1, 2, 3 and 4 respectively, that is, along the 100 same pairs of weft threads, pile threads 1, 2, 3 and 4 engage one backing in the same manner that pile threads 5, 6, 7 and 8 intersect the other backing.

Inasmuch as pile threads 3 and 4, 3 and 105 7, 7 and 8 and 4 and 8 all operate in pairs as above described, it will be understood that pile threads 4 and 7 follow precisely
